UNITED STATES PATENT OFFICE.

JULES HINDRELET, OF BROOKLYN, NEW YORK.

TOILET ARTICLE.

Application filed October 11, 1924. Serial No. 743,124.

To all whom it may concern:

Be it known that I, JULES HINDRELET, a citizen of the United States, residing at Brooklyn, in the county of Kings and State of New York, have invented new and useful 5 Improvements in Toilet Articles, of which the following is a specification.

This invention relates to toilet articles and more particularly to a combination 10 brush, comb and mirror.

Briefly stated, an important object of this invention is to provide a toilet article consisting of a shallow receptacle which forms the back of a brush and which is fashioned 15 to snugly receive a comb and a mirror in such a manner that the same may be readily exposed for use.

A further object of the invention is to provide a toilet article of the character 20 specified which is of highly simplified construction, which may be conveniently carried in a small space, and which is cheap to manufacture.

Other objects and advantages will be apparent during the course of the following 25 description.

In the accompanying drawing forming a part of this application and in which like numerals are employed to designate like 30 parts throughout the same,

Figure 1 is a perspective of the improved combination toilet article in closed position;

Fig. 2 is a perspective of the improved toilet article with the cover thereof in open 35 position to expose the comb and the mirror;

Fig. 3 is a vertical sectional view through the improved toilet article in open position;

Fig. 4 is a vertical transverse sectional view through the improved toilet article in 40 closed position.

In the drawing, wherein for the purpose of illustration is shown a preferred embodiment of the invention, the numeral 5 generally designates the back of a brush and as illustrated in Figs. 2, 3 and 4 the back 5 consists of a pair of sections 6 and 7 of the same outline and having their opposed sides formed with shallow recesses 8 and 9, respectively.

50 The shallow recess 8 in the section 6 is adapted for the reception of a mirror 3 having a spring pedestal 10 which forms a means whereby the mirror may be supported in an inclined position during the use of the same. Particular attention is directed to the fact that the spring pedestal

10 also forms a means whereby the closure section 7 is promptly swung to the open position illustrated in Figs. 2 and 3 as soon as the latch 12 carried by the section 7 is 60 released. It is believed to be obvious that the latch 12 carried by the cover section 7 is adapted to engage the edge and under side of the section 6 so as to hold the sections 6 and 7 in contact with each other 65 against the tension of the spring pedestal 10.

Fig. 2 plainly illustrates that the shallow recess 9 in the section 7 is adapted to receive a comb 16 and the ends of the shallow recess 9 are provided with extensions 20 for 70 the reception of the ends of the comb. In other words, the section 7 is provided with a shallow recess for the reception of the comb 16 and the recess is laterally enlarged between its ends for the reception of the 75 fingers so that the comb may be conveniently removed.

With reference to the foregoing description taken in connection with the accompanying drawing it will be seen that a toilet 80 article constructed in accordance with this invention is of special value to travelers since it permits the comb and the mirror to be conveniently carried within the back of a brush. In carrying out the invention, the 85 back may be of any shape and may be suitably ornamented. Also the back may be of any desired material.

In use by simply releasing the latch 12 from engagement with the section 6 the 90 spring pedestal 10 will swing the cover to open position to expose the mirror and the comb and the mirror may now be set up for use and the brush and comb conveniently employed. Of course, during the use of the 95 brush, the section 7 is returned to closed position.

Attention is also directed to the fact that the spring pedestal 10 in addition to functioning as a support for the mirror and as an opening device for the sections 6 and 7 constitutes a means to hold the comb 16 in place when the sections are in their closed position. In explaining this feature of the invention it might be said that the spring 100 10 causes the mirror 3 to bear constantly against the comb 16 when the sections are closed and this holds the comb 16 or other toilet article against movement and rattling.

Having thus described the invention, 110 what is claimed is:

1. The combination with a pair of hing-

edly connected sections having their opposed sides formed with shallow recesses, of a toilet article received in one of said recesses, a second toilet article received in the other recess and having a spring pedestal for supporting the second toilet article and for urging the sections to open position, and a latch for connecting the sections.

2. The combination with a pair of hingedly connected sections having their opposed sides formed with shallow recesses, of

a toilet article received in one of said recesses, a second toilet article received in the other recess and having a spring pedestal for supporting the second toilet article and for urging the sections to open position, said spring pedestal also constituting a means to hold the first-named toilet article in place in the recess in one of the sections. 15

In testimony whereof I affix my signature.

JULES HINDRELET.
